Specification of Letters Patent. Patented May 16, 1916.

Application filed January 23, 1911. Serial No. 604,128.

To all whom it may concern:

Be it known that we, LIBANUS M. Todd and CHARLES G. TIEFEL, of Rochester, in the county of Monroe and State of New York, have invented certain new and useful Improvements in Check-Protectors; and we do hereby declare the following to be a full, clear, and exact description of the same, reference being had to the accompanying drawings, forming a part of this specification, and to the reference-numerals marked thereon.

Our present invention relates to printing machines and particularly to that class of hand presses used for marking a check, draft or similar instruments with a limiting amount, and it has for its object to provide means for compelling the complete operation of the pressure lever after its motion has been begun, before the instrument can be removed, thus avoiding the possibility of securing an imperfect impression.

Another object is to provide means whereby the mechanism which supplies ink to the type wheel inking roller, may be readily removed from the machine for the purpose of filling or cleaning.

To these and other ends the invention consists in certain improvements and combinations of parts all as will be hereinafter more fully described, the novel features being pointed out in the claims at the end of the specification.

In the drawings: Figure 1 is a side elevation of a machine constructed in accordance with our present invention; Fig. 2 is a central vertical sectional view; Fig. 3 is a similar view showing the pressure lever operated through a portion of its stroke; Figs. 4 and 5 are fragmentary views showing subsequent positions of the lever and coöperating parts; Fig. 6 is an elevation showing the side opposite that shown in Fig. 1; Fig. 7 is a bottom plan view with the closure removed; Fig. 8 is a sectional view on the line 8—8 of Fig. 1; Fig. 9 is a sectional view on the line 9—9 of Fig. 1, looking in the direction of the arrow; Fig. 10 is a view on the same line looking in the opposite direction and showing the ink supplying mechanism in elevation; Fig. 11 is an end

view of the ink supplying mechanism removed from the machine; Fig. 12 is a similar view of the same showing the ink applying roller in adjusted position; Figs. 55 13 and 14 are sectional views on the line 13—13 and 14—14, respectively, of Fig. 11; Fig. 15 is a similar view on the line 15—15 of Fig. 6; and Fig. 16 is a similar view on the line 16—16 of Fig. 8.

Similar reference numerals throughout the several figures indicate the same parts.

The machine showing the present embodiments of the invention comprises a casing 1, provided with a narrow slot 2 to receive a check, draft or other instrument, and provided with a rounded portion above the slot for containing the printing wheel 3. This wheel carries on its periphery the printing characters, which are arranged in parallel 65 rows and are adapted to coöperate with a platen 4, located below the slot 2 and having rearwardly extending arms 5 pivoted on rods 6 extending between the lugs 7 and the sides of the casing.

The platen 4 is moved into contact with the type wheel by a lever 8 which is pivoted on an arbor or shaft 9, secured in the sides of the casing below and somewhat in rear of the platen. The lever 8 has the forwardly 80 projecting lugs 10 provided with the platen engaging portions 11, in this instance made of hardened steel balls 12, fitted into cylindrical blocks 13 preferably by drilling a hole into the end of each block and then 85 compressing or upsetting the metal around the ball slightly above the center to prevent its removal as shown in Fig. 16.

The blocks 13 are adapted to rest upon shoulders 14 formed at the bottom of recesses in the lugs 10 and to prevent their accidental withdrawal, each block 13 is provided with a reduced portion 15 which is adapted to extend through an aperture in the lug 10 below the shoulder 14. The 90 ends 15 are preferably bifurcated and are spread apart after the blocks are inserted, thereby preventing their accidental removal.

In order to insure the proper movement of the platen, away from the type wheel after an impression has been made, it is connected to the lever 8 for simultaneous move-

ment therewith by coöperating shoulders on the platen and lever, preferably in the form of a pin 16 extending forwardly from the platen, and entering an aperture 17 in a plate 18 secured to the lever.

The platen lever 8 is extended rearwardly at 19, and has pivoted thereto at (a) on both sides thereof toggle links 20, which are slotted at (b) at their opposite ends to receive the free ends of a pivot pin (c) extending through the lower end 33 of the operating lever (21) which latter projects inwardly through an aperture in the casing and is pivoted at 23 between lugs 24 on the exterior thereof.

The pivot pin (c) is prevented from disengagement with the slots (b) by a spring plate (d) pivoted at (a) to the lever 8, and having a hooked end (e) which engages the pin, said hooked end having an embossed projection (f) fitting within the slot in the adjacent link. When it is desired to disengage the links from the operating lever the spring (d) is flexed laterally a sufficient distance to clear the projection (f) and then rotated on its pivot a sufficient distance to move the hooked end (e) beyond the slot, when the parts may be separated. The lever 21 is returned to its normal position by a spring 25 which surrounds a rod 26, one end of which slides in an aperture 27 in the casing and the other being formed with a spherical head 28 fitting into a socket 29 in the lever. The ball and socket joint allows a considerable relative angular movement between the lever and rod, while the rod is moved substantially in line with the aperture 27, without lateral motion. By the use of the centering rod the spring is prevented from yielding laterally and the efficiency is increased.

It very often happens that the lever 21 is not moved its full distance, due to the fact that the toggle action requires the force applied to be constantly increased and an inexperienced user thinks that he has applied sufficient pressure, as soon as he notices a slight increase in resistance.

In order to insure the full movement of the operating lever, we provide means for preventing the retrograde movement of the lever after it has been moved a sufficient distance to bring the check it is desired to print upon, into light contact with the type wheel. In the present instance this is accomplished by pivoting at 30^a to the lever 19, a detent 30 provided with a shoulder 31 with which engages a corresponding shoulder 32 on the end 33 of the operating lever. When the lever has been actuated to the position shown in Fig. 3, giving a slight impression to the printing couple, the shoulder 31 on the detent engages the shoulder 32 on the lever and the platen is then prevented from movement away from the type wheel so that

it is impossible to withdraw the check until the lever has been moved a complete stroke.

After the lever has been moved its full stroke and a proper impression obtained it is necessary to move the detent out of the path of the shoulder 32 and to retain it in inoperative position during the return movement of the lever and this is accomplished by forming an extension 34 on the detent, which is engaged by the lever at the end of its stroke, when the detent is moved to the position shown in Fig. 4, in which position it is retained by a pawl 35 pivoted at 35^a on the lever 19 and having a shoulder 36 engaging a stop 37 on the detent 30. The detent 30 and pawl 35 are connected by a spring 38 as shown so that the normal tendency is to move the detent 30 into the path of the operating lever and the pawl 35 into the path of the stop 37. Just before the end 33 of the operating lever reaches its inward or normal position said end strikes against the end 39 of pawl 35 and withdraws the shoulder 36 from the stop 37 of the detent 30 thus allowing the shoulder 31 thereon to again move into the path of the operating lever.

The type wheel is supplied with ink by means of a felt roller 40 mounted on an arbor 41 extending through apertures in the sides of the casing, and having its ends received by plungers 42 movable in suitable guides or housings 43, and normally pressed toward the center of the type wheel by means of springs 44. In the present invention the plungers are formed by strips of half-round material bent to form loops around the ends of the arbor 41 and the ends pressed together and surrounded by the springs 44, which may have their tension varied by means of set screws 45 threaded into the rear ends of each housing. The felt roller not only serves to apply ink to the type wheel but is of such a size as to lie between the type rows and cause the proper register of the latter with the platen.

The mechanism which serves to supply ink to the inking roller 40, consists of a roller 46 of felt or similar fibrous material mounted upon the perforated tube 47 constituting a reservoir, the ends of which are loosely journaled in arms 48 and 48^a of a frame 49 preferably pivoted within the casing on a rod 50 secured to one of the side walls of the latter, and removable therefrom through an aperture 51 cut in the opposite wall. Pivoted to the arm 48 in axial alignment with the rod 50 is a cylindrical stud or post 51^a recessed to receive the end of said rod, and having secured on its outer end a centering plate 52 and a connected cover plate 53, the former being provided with laterally extending ears or lugs 54 which are adapted to enter the aperture 51 in the casing and 120

engage the walls thereof, and the latter lying outside of the casing and overlapping the edges of the aperture. Secured to the plates and projecting inwardly therefrom is 5 a post 55, slotted to receive a spring arm 56 whose free end rests above a shoulder 57 in the post 51^a, formed by cutting a groove 55^a in the latter transversely to its axis, the spring arm being adapted to drop into an 10 annular channel 58 in the rod 50 to prevent the accidental displacement of the ink supplying mechanism. To allow the insertion of the latter the rod is beveled slightly at 59 to allow the spring to be deflected and drop 15 into the notch 58. The removal of the reservoir and connected parts is accomplished by means of a headed ejecting pin 60 which is guided in the side wall of the casing opposite the aperture and adapted to bear against 20 the frame. When sufficient pressure is applied to the pin, the spring arm 56 is forced out of the channel 58 after which the mechanism can be readily withdrawn.

Journaled in the casing in proximity to 25 the frame 49 is a rock shaft 60^a having projecting pins 61 extending above the frame and a lever arm 62 secured to one end thereof outside of the casing. When it is desired to re-ink the roller 40 the lever arm is depressed thereby causing the pins to engage the frame 49 of the supply roller 46 and move the latter into contact with the inking roller. The type wheel is now rotated while the supply and inking rollers are held in 30 contact. In order to return the frame 49 a spring 63 is coiled about the post 51^a, one of its ends being secured in the groove in the post 55 and the other bearing on an extension 47^a of the tube 47, said extension passing 35 through a slot in the cover plate 53, being closed by a bifurcated plug 64 which frictionally engages in the tube and may be readily removed when it is desired to supply ink to the reservoir. The rock shaft 60^a is 40 preferably provided with a spring 65 coiled around it, one end thereof being fastened to one of the pins 61 and the other bearing against the top wall of the casing to return the lever to normal position.

45 The type wheel is preferably constructed by forming grooves or depressions 66 on the impression surfaces of the type characters which extend circumferentially of the wheel and coöperate with transverse projections 67 on the platen for the purpose of severing the paper or stretching it within the printed area to permit its fibers to absorb the ink and render alteration of the printed inscription impossible.

50 The type wheel may be secured to a shaft 67 by any suitable devices, preferably by the means shown, and is prevented from longitudinal motion by a plate 68, accurately fitting a circumferential groove 69 in the shaft and secured by screws 70 to the casing.

Fastened to the shaft of the type wheel, outside of the casing, is an indicating dial 71 having upon its face suitable figures or index marks corresponding in position to the characters on the type wheel and outside of the disk is an operating handle or knob 72 by means of which the type wheel may be rotated to bring any of the characters upon the dial into cooperative relation with a suitable index 71^a on the main frame, 70 comprising arms 72^a adapted to project over the dial 71, affording a recess 73^a therebetween with which the selected one must be aligned, the coincidence of a certain character with the index indicating that the corresponding characters on the type wheel are in proper printing position. The indicating dial 71 is secured between the operating handle 72 and a disk 73 resting against a shoulder on the shaft by a screw passing 75 through a central aperture in the operating handle and threaded into the end of the shaft. To the end that the relative position of the type wheel and indicating disk may remain unaltered, the dial is cemented to 80 the disk which has a laterally struck up portion 76 adapted to enter a key slot 77 in the shaft and the operating handle is formed of vulcanite, or similar material, which is molded, while plastic, about a metallic core 85 78 from which projects a pin 79 also entering the slot.

In order to provide means for causing the accurate register of the grooves in the type wheel and the projections on the platen, the 100 latter is preferably provided with a projecting pin 79^a engaging within an annular groove 80 in a screw 81. The latter is threaded in a side wall of the casing and its outer end is provided with a plurality of angularly arranged intersecting slots adapted to receive a laterally bent portion on a locking plate 82, secured to the casing by a fastener 83. In case it is necessary in assembling, or for other reasons, to adjust the 105 platen longitudinally the locking plate 82 is removed, the screw 81 moved the desired distance, the slots in this instance admitting adjustments differing by one eighth of a revolution of the screw, and the locking plate replaced. 110

The machine may be mounted on a suitable base or support, preferably formed of sheet metal, having a horizontal platform 84 projecting beyond the casing on all sides, 115 and the inclined walls 85 depending therefrom. The base is closed by a cover 86 formed by a plate preferably of sheet metal 87, and provided with a suitable covering of cloth or other similar material, adapting the 120 machine to be used on a polished desk without marring the same. The cover rests against Z-shaped brackets 88, the outer end of which are in the plane of the lower edge of the base and fit in depressions 89 on the 125 130

lower edges of the inclined walls 85, the inner ends being bent into contact with the horizontal platform 84 and secured by fasteners in the form of screws 90 passing 5 through the base and threaded into the lower corners of the casing. The center of the horizontal portion of the base is removed and the cover is prevented from accidental displacement by spring arms 91 thereon adapted to engage shoulders 83^a formed by notches in the edge of the aperture, to hold the cover in contact with the brackets 88. A headed pin or plunger 93 is guided in a sleeve 94 depending from the 10 platform in rear of the casing, and its lower end normally rests upon the cover, which may be readily detached, if desired, by pressure upon the plunger.

The arbor 9 of the lever 8 which co-operates with the platen is preferably constructed so as to be quickly removed in order to gain access to the interior mechanism of the machine, and to this end a depression 95 is formed in one of its supporting ends, to receive a plunger 96 guided at 97 in the casing and its outer end 98 passing through an aperture 99 in the base platform. The plunger is actuated by a spring 100 interposed between a shoulder 101 thereon and the base plate. One end of the arbor is provided with a knob or finger piece and the opposite end is beveled as is also one wall of the groove 95, that the arbor may be either inserted or removed, by applying thereto 30 sufficient pressure to overcome the resistance of the spring 100.

It is desirable that the pawl 35 and detent 30 be mounted so as to be readily removed for facilitating fitting during the process of 40 manufacture or for gaining access to the inking mechanism for any desired purpose, and we therefore mount them in this instance on the lever 8 although any readily removable support might be used.

45 The extreme end of the pressure lever at the point where the power is applied is preferably slightly rounded and highly finished to give a pleasing appearance, and to this end we make a handle portion of two disks 50 100 and 101 of sheet metal the inner disk 101 being formed with a recess to receive a nut 102, and the outer disk 100 superposed upon and its edges turned beneath the disk 101 to secure the nut between them. A fastener or 55 screw 103 passing through the lever from its under side serves to secure the disk against a seat 104 thereon.

By making the handle portion removable the finishing thereof is facilitated and in 60 case of injury or wear it may be easily removed and another substituted therefor.

A machine constructed in accordance with our invention is neat in appearance, as most of the operating parts are concealed 65 within the casing, and all of the parts con-

tribute to ease and convenience of operation.

We claim as our invention:

1. In a check protector, the combination with a printing couple comprising two parts 70 one of which is movable relatively to the other, of two co-operating movable members for actuating the movable part, of means carried on one of the members and co-operating with the other member after the relative movement of the members in one direction has commenced for preventing its movement in the opposite direction, and a retaining device engaging and holding said means in an inoperative position when the 80 members reach the limit of their movement, said retaining device being adapted to be actuated by one of the members to release said means as the members approach the limit of their movement in the opposite 85 direction.

2. In a check protector, the combination with a printing couple comprising a stationary member and a platen and two co-operating movable members for actuating the 90 platen, of a full stroke mechanism comprising means co-operating with one of the members when they are moved in a direction to actuate the platen into printing position, said means being adapted to insure the continued movement of the member in this direction until the desired pressure has been exerted on the platen, and a retaining device adapted to co-operate with said means to hold it in an inoperative position during the 100 movement of the members in the opposite direction.

3. In a check protector, the combination with a stationary type form, and a platen co-operating therewith, an arm for operating 105 the platen and a lever for actuating the arm, of a latch adapted to co-operate with the lever when it has been moved part way in one direction to arrest its return, and a catch engaging the latch to hold it in inoperative position when the lever has moved a predetermined distance.

4. In a check protector, the combination with a stationary type form, a platen co-operating therewith and a toggle for operating 115 the platen, of mechanism co-operating with the toggle to insure the movement of the platen a predetermined distance, comprising a latch adapted to be interposed in the path of the toggle after it has commenced its movement in one direction, and means for moving the latch out of the path of the toggle and retaining it in an inoperative position after the platen has been moved a predetermined distance.

5. In a check protector, the combination with a stationary type form and a platen, and a toggle for operating the platen comprising two co-operating lever arms, which, when moved in one direction actuate the 120

5 platen toward the type form, of means carried on one of said arms and coöperating with the other for locking them against movement in the other direction, said means being adapted to become inoperative when the toggle has been operated to move the platen a predetermined distance.

6. In a check protector, the combination with a type form and a platen, of toggle 10 levers for operating the platen in a direction toward the type form, means coöperating with said levers to prevent their movement in the opposite direction, and a member coöperating with said means to hold it in 15 an inoperative position after the levers have been moved sufficiently to actuate the platen into a predetermined position.

7. In a check protector, the combination with a stationary type form, a platen and 20 toggle levers coöperating with the latter when moved in one direction to actuate it in a direction toward the type form, of a latch carried on one lever and coöperating with the other to limit the movement of the 25 levers in the other direction, and a catch adapted to engage the latch to hold it in an inoperative position when the levers have been moved sufficiently to actuate the platen a predetermined distance.

8. In a check protector, the combination with a type form, a platen and a toggle coöperating with the latter to move it in a direction toward the type form, comprising two pivoted levers, and an operating 30 connection between them, of a latch pivoted on one lever having a projection movable into the path of the other lever when the toggle is moved in one direction, and provided with a part adapted to subsequently 35 engage said lever to move said latch projection out of the path of said other lever, and a catch coöperating with the latch in the last mentioned position and holding it during the return movement of the levers.

9. In a printing mechanism, the combination with a printing couple, a pressure lever coöperating with one of the members of the couple, and an operating lever connected to the pressure lever, of a detent pivoted to the 45 pressure lever and adapted to coöperate with the operating lever when a portion of the printing stroke is completed by the movement of said levers in one direction, an abutment on the detent engaging the operating lever as it approaches the end of its movement, a latch on the pressure lever adapted to engage the detent to hold it out of coöoperative relation with the operating lever during the movement of said levers 50 in the opposite direction to permit a separation of the printing couple, said latch being adapted to engage the operating lever during its return movement to release the detent.

10. In a printing mechanism, the combination with a printing couple, two coöp-

erating levers pivoted to swing in intersecting arcs and an operating connection between them, one of said levers acting as a pressure lever for operating one of the members of the printing couple, the other constituting an actuating member for the pressure lever, of a detent pawl yieldingly supported on one lever and adapted to engage the other to prevent return movement of the actuating member when it has been moved part 70 of its stroke in actuating direction, means for moving said pawl into an inoperative position upon completion of the stroke of said member, and a device for retaining the pawl in this position during return of said member which is subsequently operated to release the pawl as the levers approach their normal positions.

11. In a check protector, the combination with a type form, a platen coöperating therewith and a pressure lever acting on the platen, an actuating lever pivoted to one side of the pressure lever and having an extremity located in proximity to the pressure lever and a toggle connecting said levers, of 85 a pawl on the pressure lever adapted to move in rear of the end of the actuating lever as the latter moves in one direction to effect the operation of the platen, means for carrying the pawl out of the path of said lever as the latter completes its stroke, a spring operated latch coöperating with the pawl to hold it in this position, said latch also coöperating with the end of the actuating lever as it returns to normal position to 90 release the pawl.

12. In a check protector, the combination with a frame, a type wheel therein, a platen underlying it, and a pressure lever pivoted beneath and coöperating with the platen 105 having a rearwardly projecting end, an actuating lever pivoted on the frame in rear of the type wheel having an end lying in juxtaposition to the pressure lever and a toggle connecting said levers, of a member 110 on the pressure lever having two projections adapted to coöperate with the forward and rear sides of the actuating lever, one projection operating to prevent the movement of the lever in one direction and the other for moving the member to carry the first mentioned projection into an inoperative position, and a latch coöperating with the member to hold it in such position temporarily, 115 said latch also coöperating with the end of the actuating lever to release said member.

13. In a check protector, the combination with a type form, a platen and a pressure lever for operating it, of a pivoted pawl and a latch coöperating therewith to hold it in 120 an inoperative position, but normally disengaged therefrom, both the pawl and latch being mounted on said lever, said pawl being provided with two projections, and an operating lever for actuating the pressure 125

lever having a portion lying between the pawl and latch and coöperating with said parts.

14. In a check protector, the combination with a type form, a platen and a pressure lever for operating it, of a pawl and a latch on said lever and movable toward each other, the pawl being provided with a projection adapted to be engaged by the latch to hold it in an inoperative position and also having a stop tooth and a tripping finger, and a lever for actuating the pressure lever provided with a portion lying between the pawl and latch and operating when the lever is moved in one direction to successively engage the stop tooth and finger, and when moving in the other direction to trip the latch.

15. In a printing mechanism, the combination with a type form, a platen, a lever for operating the platen provided with recesses, of blocks arranged in said recesses and having reduced extensions adapted to pass through the lever, and bearing balls carried on said blocks and coöperating with the platen.

16. In a printing mechanism, the combination with a type form, a platen, a lever for operating the platen provided with recesses in its face and openings extending from said recesses through the lever, of blocks arranged in the recesses and having reduced extensions which are bifurcated and disposed in the aforesaid openings, extending beyond the lower face of the lever, and bearing balls secured in the blocks and co-operating with the platen.

17. In a check protector, the combination with a closed casing, a type wheel journaled therein, a platen, and an inking roller coöperating with the wheel, of an ink supply roller, a frame in which it is journaled removably inserted through an aperture in the side of the casing into juxtaposition with the inking roller, a cap connected to the frame and normally closing said aperture and a spring arranged between the cap and frame for moving the supply roller away from the inking roller, and means for moving said frame in the opposite direction.

18. In a check protector, the combination with a casing comprising side walls one of which is provided with an aperture, a printing wheel journaled in the casing, a platen and an inking roller coöperating with the wheel, of a guide rod supported on one side wall, a frame insertible through the aperture in the other side wall and supported on the rod, and a supply roller carried in the frame, a cap for closing said aperture connected to the frame and means for moving the latter to carry the supply roller into engagement with the inking roller.

19. In a check protector, the combination

with a casing comprising side walls one of which is provided with an aperture, a printing wheel journaled in the casing, a platen and an inking roller coöperating with the wheel, of a cap for closing said aperture, a frame journaled on the cap and a supply roller journaled on the frame and extending transversely of the casing, a spring arranged between the cap and frame for moving the latter in one direction, a rock shaft journaled in the casing having an operating lever arranged exteriorly of the casing and provided with fingers coöperating with the frame to move it in the opposite direction.

20. In a check protector, the combination with a casing comprising side walls one of which is provided with an aperture, a printing wheel journaled in the casing, a platen and an inking roller coöperating with the wheel, of a closure for said aperture, a frame journaled on the closure and extending transversely of the casing, a supply roller carried on the frame, means for moving the roller into and out of engagement with the inking roller and a push pin adapted to engage the inner end of said frame to project its opposite extremity from the aperture.

21. In a check protector, the combination with a casing comprising side walls one of which is provided with an aperture, a printing wheel journaled in the casing, a platen and an inking roller coöperating with the wheel, of a closure for said aperture, having spring fingers engaging the edges of said aperture, a frame movably supported on the closure and extending transversely of the casing and a supply roller having bearings at its ends journaled on the frame, one of said bearings being extended through the closure to form a handle, a spring arranged between the closure and frame, a push pin supported on the casing and adapted to operate with the frame to move it and disengage the closure from the aperture.

22. In a printing mechanism, the combination with a casing having an aperture in one side thereof, a type wheel journaled in the casing and an inking roller therefor, of a supply roller for transferring ink to the inking roller, and removable through the aperture, a spring retainer detachably holding the roller in position in the casing and an ejector for projecting the frame from said aperture against the action of the retaining device.

23. In a printing mechanism, the combination with a casing having an aperture in one side thereof, a type wheel journaled in the casing and an inking roller therefor, of a rod secured to one wall of the casing having a notch therein, a frame pivotally held on the rod and carrying a supply roller, a tubular post on the frame receiving the end of the rod and provided with a notch, a

- centering plate secured to the post, and a spring finger carried by the centering plate and entering the notches in the rod and post.
- 5 24. In a printing mechanism, the combination with a casing having an aperture in one side thereof, a type wheel and an inking roller therefor, a rod secured to one wall of the casing, a frame pivoted on the rod, and 10 a supply roller journaled in the frame, of a post pivoted to the frame in axial alinement with the rod, a centering plate secured to the post and fitting the aperture in the casing and a spring operating on the frame and 15 plate to normally hold the former roller out of engagement with the inking roller.
25. In a printing mechanism, the combination with a type wheel, a platen and an inking roller, a casing containing said parts 20 having side walls one of which is provided with an aperture, of a closure removably fitting the latter and also provided with an aperture, an ink supply roll removably supported on the closure and adapted to co- 25 operate with the inking roller, a reservoir arranged within the supply roll having an open end accessible through the aperture in the closure and a plug fitting said end of the reservoir and adapted to serve as a 30 handle by means of which the supply roll and closure may be manipulated when detached from the casing.
26. In a printing mechanism, the combination with a casing, a type wheel therein 35 having type characters thereon provided with circumferential grooves, of a grooved platen, an adjusting screw threaded in the casing having an annularly recessed inner end coöperating with the platen, and an 40 outer end provided with a plurality of slots and a locking member on the casing coöperating with one or another of said slots.
27. In a check protector, the combination with a casing having a bottom, a type form 45 and a platen therein, of a sheet metal base having a platform fitting the bottom of the casing and provided with depending flanges, rest pieces each having a foot extending horizontally into engagement with the bottom 50 corner edges of the base and an upwardly and laterally extending end lying in engagement with the platform, securing devices passing through said ends and the plat-
- form and engaging the casing, and a closure for the base engaging the rest pieces. 55
28. In a check protector, the combination with a casing, and a rectangular base therefor embodying a platform having depending walls the lower edges of which are offset outwardly, of rest brackets fitted in the corners 60 of the base, their extremities lying in said offset portions and supporting said corners and a closure for the base engaging said brackets.
29. In a check protector, the combination 65 with a casing, a type wheel, an arbor supporting the latter and journaled in the casing, having a projecting slotted end and provided with a shoulder, of a disk resting against the shoulder having a projection, an 70 operating handle also having a projection and secured to the arbor, an index dial clamped between the operating handle and disk, the projections on the operating handle and disk entering the slot in the arbor. 75
30. In a check protector, the combination with a casing, a type wheel, an arbor therefor journaled in the casing having a projecting slotted end provided with a shoulder, of a disk resting against the shoulder and 80 having a key projection entering the slot, an operating handle having a core, a pin projecting therefrom into the slot in the arbor, an indicating dial adjustably clamped between the operating handle and disk and a 85 fastener securing the handle to the arbor.
31. In a check protector, the combination with a printing couple comprising a stationary type carrier and a platen; and a plurality of coöperating movable members for actuating the platen; of a full stroke mechanism comprising locking means coöperating with one of said members when the latter is moved in a direction to actuate the platen, for preventing the return of said member 90 until the printing impression is completed, and comprising also means for releasing said locking means after the impression and for holding it inoperative to permit the return of said member to starting position. 95
